UNITED STATES PATENT OFFICE.

FREDERICK CRANE, OF NEWARK, NEW JERSEY.

DESIGN FOR HARNESS-TRIMMING.

SPECIFICATION forming part of Design No. 13,561, dated January 30, 1883.

Application filed October 23, 1882. Term of patent 14 years.

To all whom it may concern:

Be it known that I, FREDERICK CRANE, of Newark, in the county of Essex and State of New Jersey, have originated and invented a new and useful Design for Harness-Trimming; and I do hereby declare that the following is a full, clear, and exact description thereof, reference being had to the accompanying drawings, forming a part of this specification. Figure 1 is an edge view of a terret and a side elevation of the same. Fig. 2 is a front view of a buckle. These are representative articles, and the other portions of the solid hardware portions of harness-trimmings may be finished off in the same way.

The chief feature of my design is the trans-

verse corrugated exterior, formed by hollowing out small portions of the metal, so as to produce the effect shown in the accompanying drawings.

20

I claim—

The terret, buckle, or other harness-trimming having the exterior surface corrugated transversely, substantially as set forth.

In testimony that I claim the foregoing as 25 my own I affix my signature in presence of two witnesses.

FREDERICK CRANE.

Witnesses:

ARTHUR M. CRANE,
WILLETT CHADWICK.
